UNITED STATES PATENT OFFICE

152,444

DESIGN FOR A BOAT

Clyde A. Ward, San Francisco, Calif.

Application May 5, 1947, Serial No. 138,819

Term of patent 3½ years

(Cl. D71—1)

To all whom it may concern:

Be it known that I, Clyde A. Ward, a citizen of the United States, residing at San Francisco, in the county of San Francisco and State of California, have invented a new, original, and ornamental Design for a Boat, of which the following is a specification, reference being had to the accompanying drawing, forming part thereof.

Fig. 1 is a side elevation of a boat, showing my new design.

Fig. 2 is a top plan view of my boat,

Fig. 3 is an end elevation of my boat, and

Fig. 4 is a top perspective view.

I claim:

The ornamental design for a boat, as shown.

CLYDE A. WARD.
